(57) **CLAIM**

The ornamental design for a feeding implement, as shown and described.

DESCRIPTION

FIG. 1 is a perspective view of a feeding implement of my new design;

FIG. 2 is a top plan view of the feeding implement of FIG. 1, the bottom plan view being the same image;

FIG. 3 is a left side elevational view of the feeding implement of FIG. 1, the right side being a mirror image;

FIG. 4 is a front elevational view of the feeding implement of FIG. 1; and,

FIG. 5 is a rear elevational view of the feeding implement of FIG. 1.

The handle is shown in broken lines for illustrative purposes only and forms no part of the claimed design.
